UNITED STATES PATENT OFFICE.

THOMAS J. MAGNER AND CHARLES L. THOMAS, OF HORNELLSVILLE, N. Y.

FIFTH-WHEEL FOR VEHICLES.

SPECIFICATION forming part of Letters Patent No. 239,262, dated March 22, 1881.

Application filed January 8, 1881. (Model.)

To all whom it may concern:

Be it known that we, THOMAS J. MAGNER and CHARLES L. THOMAS, of Hornellsville, in the county of Steuben and State of New York, have invented a new and valuable Improvement in Fifth-Wheels for Vehicles; and we do hereby declare that the following is a full, clear, and exact description of the construction and operation of the same, reference being had to the annexed drawings, making a part of this specification, and to the letters and figures of reference marked thereon.

Figure 1 of the drawings is a front view. Fig. 2 is a section taken the length of the device. Fig. 3 is a plan view.

This invention relates to fifth-wheel connections for vehicles.

The invention consists in the construction hereinafter described and claimed.

In the drawings hereto annexed, A is the front axle, supporting on its top the lower member, B, of the fifth-wheel connections. This member B consists of a bar, C, having at its ends the circle-bars b b on top, and the perforated lugs e e depending from said ends, and at its middle the lower fifth-wheel plate, D, having the perforated lugs d d, extending downward, and a central boss, d', projecting upward, said boss having a hole, d'', there-through countersunk below at d''. This member, as described, is to be cast in one piece. It is seated upon the top of axle A, the latter fitting snugly between the depending lugs, and bolts are passed through said lugs, and held below by tie-plates e and nuts e', the heads of said bolts being countersunk into tops of circle-bars b b and lower fifth-wheel plate, D.

The upper member, F, of the fifth-wheel connections consists of a bar, G, similar to bar C, having at its ends, on the lower side, circle-bars f f, fitting and corresponding with circle-bars b b of the lower member, fins g g, projecting upward at said ends, and midway between these pins a hole countersunk below, at its middle, upon the lower side, the upper fifth-wheel plate, H, having central perforation, h, corresponding to and to receive central boss, d', of the lower plate, D, having a perforated lug, h', projecting forward, and the arm I backward and downward, to be attached to the reach, fins g' g', projecting upward at

the fifth-wheel plate H, and ribs K K, midway between such plate and the circle-bars, terminating at each side in the perforated lugs k k. 55 This member, as described, is to be cast in one piece. The bolster or head-block L is seated thereon between the fins and lugs described, fitting snugly, and is held by bolts M M passing through the ends of the bolster and 60 holes in bar G.

The perforations in lugs d d are countersunk at the top, and passing through said perforations, with heads resting in the countersinks, are bolts N N, fitting close on each 65 side of the axle, and held below the same by tie-plate N' and nuts n n. Projecting downward from the middle, and integral with said tie-plate N', is a stud, P, having collar p and reduced screw-threaded end p'.

R is a brace-arm, attached to the under side of the reach, corresponding to arm I. This arm extends under the axle, and has a perforation, r, at its end, and another, r', where stud P comes. This stud passes through perforation r', is held by nut p', and swivels in said perforation r'.

S is a bolt passing through perforated lug h' and perforation r' of arm R.

T is the king-bolt, its head resting in countersink d' of hole d'', its body t passing through said hole, said body being round where it rests in the boss d', and up through the bolster L, where it is made angular, and said bolt being held at top by nut t'.

The bolts N N, clasping the front axle, take the place of the cheek-pieces of the ordinary clip king-bolt, and, together with the king-bolt T, supply the place of said clip king-bolt. The central boss, d', and the swivel-connection of the stud P with arm R, form the turning-points in cramping. The king-bolt, being held rigid by its angular portion in the bolster, turns by its round portion within the central boss.

V V are the clips for holding the spring to the bolster, their ends being held in lugs k k.

Instead of using only one bar I, running from the reach to the upper fifth-wheel plate, we may use two such bars running to the plate, 100 or to the bar G when used for a double-reach buggy.

Instead of using the bolt S, the arm R may be extended up around and joined to the lower

side of the upper fifth-wheel plate, H, at the lug h' .

What we claim is—

1. The lower fifth-wheel plate, D, having 5 perforated lugs $d d$ and central perforated boss, d' , bolts $N N$, tie-plate N' , having stud P, with collar p and screw-threaded reduced end p' , and upper fifth-wheel plate, H, having central perforation, h , in combination with 10 king-bolt T, having its body round below and angular above, substantially as and for the purpose described.

2. The lower member of the fifth-wheel connection, consisting of bar C, circle-bars $b b$, 15 perforated lugs $c c$, lower fifth-wheel plate, D, having perforated lugs $d d$ and perforated central boss, d' , all made in one piece, in combination with the upper member, consisting of bar G, circle-bars $f f$, fins $g g$, upper fifth- 20 wheel plate, H, having central perforation, h , perforated lug h' , and arm I, fins $g^3 g^3$, and

ribs K K, having perforated lugs $k k$, all made in one piece, substantially as described.

3. The combination of king-bolt T, bolts N N, lower fifth-wheel plate, D, upper fifth-wheel 25 plate, H, having arm I, and tie-plate N' , all constructed and arranged substantially as and for the purpose described.

In testimony that we claim the above we have hereunto subscribed our names in the 30 presence of two witnesses.
